US0D1062168S

(12) **United States Design Patent** (10) Patent No.: **US D1,062,168 S**
(45) Date of Patent: ** Feb. 18, 2025

(54) **SHOE**

(71) Applicant: **Birkenstock IP GmbH**, Linz am Rhein (DE)

(72) Inventor: **Arno Marchand**, Linz am Rhein (DE)

(73) Assignee: **Birkenstock IP GmbH**, Linz am Rhein (DE)

(**) Term: **15 Years**

(21) Appl. No.: **35/518,623**

(22) Filed: **Sep. 13, 2023**

(80) **Hague Agreement Data**

Int. Filing Date: **Sep. 13, 2023**

Int. Reg. No.: **DM/231938**

Int. Reg. Date: **Sep. 13, 2023**

Int. Reg. Pub. Date: **Oct. 13, 2023**

(30) **Foreign Application Priority Data**

(57) **CLAIM**

The ornamental design for a shoe as shown and described.

DESCRIPTION

12. Shoe
13. Shoe
12.1 : Left
12.2: Top
12.3: Right
12.4 : Perspective
12.5: Back
12.6 : Bottom
12.7: Front
13.1 : Left
13.2: Top
13.3: Right
13.4 : Perspective
13.5: Back
13.6 : Bottom
13.7: Front

1 Claim, 14 Drawing Sheets
